UNITED STATES PATENT OFFICE.

GEORGE DAMER, OF THE UNITED STATES NAVY.

PROJECTILE.

1,205,715.

Specification of Letters Patent. Patented Nov. 21, 1916.

Application filed May 24, 1916. Serial No. 99,489.

To all whom it may concern:

Be it known that I, GEORGE DAMER, of the United States Navy, a citizen of the United States, have invented a new and Improved Projectile, of which the following is a full, clear, and exact description.

The object of the invention is to provide a new and improved projectile more especially designed for destroying wire entanglements, aerial craft, masts, fighting tops, wireless aerials and like structures, and which is very simple and durable in construction and arranged to permit of firing the projectile from a gun the same as an ordinary projectile and without danger of injuring the bore of the gun.

In order to produce the desired result, use is made of raking members pivoted on the body of the projectile and adapted to slide 20 in the direction of the axis of the projectile while in folded position, and retaining means to hold the raking members in folded forward position and to allow the raking members to slide rearwardly into released 25 position owing to the inertia thereof on the firing of the projectile so that the raking fingers are subsequently swung upward and rearward into open position. Use is also made of abutments on the projectile to limit 30 the rearward swinging motion of the raking members with a view to hold the latter in an acute angle position relatively to the axis of the projectile.

A practical embodiment of the invention 35 is represented in the accompanying drawings forming a part of this specification, in which similar characters of reference indicate corresponding parts in all the views.

Figure 1 is a plan view of the projectile; 40 Fig. 2 is a longitudinal central section of the same on the line 2-2 of Fig. 1; Figs. 3 and 4 are sectional side elevations of the rear end of the projectile and showing the successive steps for placing a raking member 45 in position on the body of the projectile; Fig. 5 is a sectional side elevation of the same showing the raking member in extended active position after the projectile is fired; Fig. 6 is a sectional side elevation of 50 the rear end of the projectile on the line 6-6 of Fig. 1 and showing more particu-

larly the filling block in position after the raking member is inserted; Fig. 7 is a plan view of a portion of the projectile with one of the raking arms in rearward released position; Fig. 8 is a cross section of the projectile on the line 8-8 of Fig. 1; Fig. 9 is a similar view of the same on the line 9-9 of Fig. 1; and Fig. 10 is a similar view of the same on the line 10-10 of Fig. 1.

The body 15 of the projectile is of the usual shape and is provided on its peripheral face with a series of longitudinally extending recesses 16 in each of which is held a raking member 17 extending therefrom beyond the point of the body 15 and adapted to swing outward and rearward into an acute angle position, as indicated in Fig. 5. Each of the raking members 17 is provided at its rear end with an open eye 18 adapted 70 to engage a transverse pivot 19 attached to or forming part of the body 15 and extending into the enlarged rear portion 20 of the corresponding recess 16. Each raking member 17 is preferably in the form of 75 a bar of triangular shape in cross section to provide a cutting edge 21 at its bottom and each bar terminates at its outer end in a hook 22. The raking member 17 when in folded position extends within the peripheral face 80 of the body 15 and consequently of the bore of the gun from which the projectile is fired.

The enlarged portion 20 of the recess 16 and the eye 18 of a raking member 17 are 85 so constructed that each raking member is mounted to slide lengthwise, that is, from a normal forward position as shown in Figs. 1 and 2 to a rearmost position as illustrated in Fig. 7. When the raking member 17 is 90 in a forward position it is held clamped in this position to prevent accidental opening of a raking member and for this purpose each side of a raking member 17 is provided with raised clamping portions 25 95 clampingly engaging the corresponding portions 26 formed on the side walls of the recesses 16 (see Figs. 1, 2 and 7). When the projectile is fired the percussion action incident thereto causes the raking member 17 100 to slide rearwardly and in doing so the clamping portions 25 move out of engage-

ent with the clamping portions 26 (see Fig. 1), thus freeing the raking members and allowing the same to swing upward and rearward into open position.

The upward and rearward swinging movement of the raking members 17 is limited by abutments 30 formed integrally on the rear walls of the enlarged portions 20 of the recesses 16, the said rear walls being bent forward at the upper portions to provide an overhang, as will be readily understood by reference to Figs. 1, 2, 4 and 5.

In practice the enlarged portion 20 of each recess 16 is extended to one side of its recess to permit of conveniently hooking the eye 18 on the pivot 19 and then moving the eye 18 transversely along the pivot 19 until the raking member 17 is in register with the corresponding recess 16 to allow of swinging the raking member into folded position. After the raking member is in position a filling block 40 is placed in the extension of the enlarged portion 20 to prevent accidental return movement of the eye 18 on the pivot 19 at the time the corresponding raking member is in open position. The filling lock 40 is preferably fastened in place by screw 41 and the filling block is provided with a slot 42 extending from the bottom upward to straddle the pivot 19, as will be readily understood by reference to Fig. 6.

From the foregoing it will be seen that when the projectile is fired from the gun the raking members 17 swing into an acute angled position relative to the axis of the body 15 so that the cutting edges 21 of the raking members readily cut through wire entanglements, shells of balloons and the like, and the hooks 22 readily hook onto the surrounding parts of the structures to carry the same along and to tear such structures asunder.

The raking members 17 shown and described are very simple and durable in construction and are especially serviceable for use on projectiles up to, say, six inches in diameter.

The projectile is very serviceable for use in guns mounted on aeroplanes and other aerial vessels for fighting enemies' aerial raid.

Having thus described my invention, I claim as new and desire to secure by Letters Patent:

1. A projectile, comprising a body provided in its peripheral face with longitudinal grooves spaced equidistantly apart, pivots extending transversely at the rear portions of the said grooves, and raking members mounted to slide in the direction of their length and to swing on the said pivots by the inertia thereof on the firing of the projectile.

2. A projectile, comprising a body provided in its peripheral face with longitudinal grooves spaced equidistantly apart, pivots extending transversely at the rear portions of the said grooves, and raking members mounted to slide longitudinally and to swing on the said pivots, the said raking members and the side walls of the said grooves having relatively engaging means to normally hold the raking members in forward folded position, disengageable by rearward movement of the said raking members by the inertia thereof on the firing of the projectile, whereby to allow the raking members to swing upward into extended active position.

3. A projectile, comprising a body provided in its peripheral face with longitudinal grooves spaced equidistantly apart, pivots extending transversely at the rear portions of the said grooves, and raking members mounted to slide and to swing on the said pivots, the said raking members being provided at their sides with raised portions and the side walls of the grooves being provided with raised clamping portions normally engaged by the said raised portions of the raking members to hold the latter normally in forward position, the said raking members on sliding rearward moving their raised portions out of engagement with the clamping portions on the groove walls to allow the raking members to swing into open position.

4. A projectile, comprising a body provided in its peripheral face with longitudinal grooves, the rear end wall of each of which grooves is provided at the top with a forwardly extending overhanging abutment, pivots extending transversely through the rear portions of the said grooves, and raking members mounted to slide and swing on the said pivots and normally folded in the said grooves, the pivotal ends of the raking members being adapted to engage the said abutments to limit the outward and rearward swinging motion of the raking members.

5. A projectile, comprising a body having longitudinal grooves, raking members pivoted in the grooves of the said body and adapted to slide on their pivots in the direction of the axis of the projectile, said raking members extending beyond the end of the projectile and retaining means to hold the raking members in folded forward position and to allow the raking members to slide rearward into released position by the inertia thereof incident to the firing of the projectile whereby to allow the raking fingers to subsequently swing upward and rearward.

6. A projectile, comprising a body, raking

ing members pivoted on the said body and adapted to slide on their pivots in the direction of the axis of the projectile, said raking members extending beyond the front 5 end of the projectile, retaining means to hold the raking members in folded forward position and to allow the raking members to slide rearward into released position by the inertia thereof incident to the firing of the

projectile whereby to allow the raking fingers to subsequently swing upward and rearward, and abutments on the projectile to limit the rearward swinging motion of the raking members to hold the latter in an acute angle position relatively to the axis of 10 the projectile.

GEORGE DAMER.
